UNITED STATES PATENT OFFICE

THOMAS W. SMITH, JR., OF BARBERTON, OHIO, ASSIGNOR TO THE SUN RUBBER COMPANY, OF BARBERTON, OHIO, A CORPORATION OF OHIO

DESIGN FOR A TEETHING RING

Application filed February 15, 1933. Serial No. 47,224. Term of patent 7 years.

To all whom it may concern:

Be it known that I, THOMAS W. SMITH, JR., a citizen of the United States, and a resident of Barberton, in the county of Summit and State of Ohio, have invented a new, original, and ornamental Design for a Teething Ring, of which the following is a specification reference being had to the accompanying drawing, forming a part thereof.

In the drawing:

Figure 1 is a front elevation of a teething ring showing my new design;

Figure 2 is a rear elevation thereof; and

Figure 3 is a perspective view thereof.

I claim:

The ornamental design for a teething ring as shown.
